Attorneys

UNITED STATES PATENT OFFICE.

ARTHUR E. WHITNEY, OF WILLIAMSTOWN, VERMONT.

AIR FEED FOR STOVES.

Application filed September 7, 1921. Serial No. 499,119.

To all whom it may concern:

Be it known that I, ARTHUR E. WHITNEY, a citizen of the United States, residing at Williamstown, in the county of Orange and 5 State of Vermont, have invented new and useful Improvements in Air Feed for Stoves, of which the following is a specification.

This invention relates to devices for feeding air to the fire pots of cooking stoves and 10 ranges to promote combustion, and its object is to provide a very simple and efficient device of this kind arranged to permit the air to become heated before it is discharged into the fire pot.

15 The object stated is attained by means of a novel combination and arrangement of parts to be hereinafter described and claimed, and in order that the same may be better understood, reference is had to the 20 accompanying drawing, wherein—

Figure 1, is a plan view of the improved stove, partly cut away to disclose the interior;

Fig. 2, is a vertical section, and

25 Fig. 3, is a detail view in perspective.

Referring specifically to the drawing, 5 denotes the body of a cooking stove of standard design. In Fig. 1 the top plate 6 carrying the lids is shown partly broken away to 30 expose the parts located in the top chamber 6^a through which the products of combustion pass from the fire pot 7 to the smoke flue 8.

In the chamber 6^a is located an air-feeding 35 pipe 9 having one end passing through the rear wall of said chamber and here provided with a suitable damper 10 for controlling the admission of air to the pipe.

The pipe 9 extends horizontally through 40 the chamber 6^a to the fire pot 7, and to its outlet end is fitted a downturned nozzle having an elbow-shaped body 11.

The nozzle body 11 is positioned between 45 the two fire bricks 13 forming the rear lining of the fire pot 7, and the bottom of the nozzle body has a discharge opening 12 into the fire pot. In the inner faces of the fire bricks 13 are air channels or passages 14 leading from the inner edges of the same, 50 near the top thereof, and opening through

the bottom into the fire pot to provide air outlets 15 on opposite sides of the nozzle outlet 12.

The back of the nozzle body fits snugly against the rear fire pot wall 16 which is 55 faced with the bricks 12, and this portion of the nozzle body has a central vertical passage or channel 17 communicating at its upper end with the pipe 9, and leading to the outlet 12. From this passage extend side 60 branches or ducts 18 which lead to the passages 14, the latter and the ducts extending obliquely in opposite directions from the main passage 17.

It will be evident from the foregoing that 65 the air passing through the pipe 9 is discharged into the fire pot 7 near the bottom thereof through the outlets 12 and 15, the air being delivered at three points which are spaced in the direction of the length of the 70 fire pot. The air is heated in its passage through the pipe 9, and as the outlet nozzle extends into the fire pot, the air is further heated in its travel through the passages 17 and ducts 18, and also in its travel through 75 the passages 14 in the highly heated fire bricks 13. The volume of air to be supplied is readily controlled by the damper 10 at the inlet end of the pipe 9.

I claim:

1. The combination with the fire pot of a stove and the top chamber leading therefrom; of an air feeding pipe extending through said chamber and provided with an inlet, said pipe leading to the fire pot and 85 having a depending nozzle thereat extending into the same and having a bottom outlet, and a lining for the rear wall of the fire pot, said lining being in sections which are spaced at their adjacent ends, the nozzle being located between said ends, said lining sections having air-passages opening into the fire pot, and the nozzle having air delivery ducts opening into said passages. 90

2. The combination with the fire pot of a 95 stove and the top chamber leading therefrom; of an air feeding pipe extending through said chamber and provided with an inlet, said pipe leading to the fire pot and having a depending nozzle thereat extend- 100

ing into the same and having a bottom outlet, and a lining for the rear wall of the fire pot, said lining being in sections which are spaced at their adjacent ends, the nozzle being located between said ends, and having its rear face seating against said fire pot wall, the lining sections having air passages

opening into the fire pot, and the rear face of the nozzle body having an air delivery passage leading to the aforesaid bottom outlet, and provided with side branches leading to the lining passages. ¹⁰

In testimony whereof I affix my signature.

ARTHUR E. WHITNEY.
